UNITED STATES PATENT OFFICE.

JOSHUA KIDD, OF FERN BANK, WANDSWORTH COMMON, COUNTY OF SURREY, ENGLAND.

APPARATUS FOR ENRICHING GAS.

SPECIFICATION forming part of Letters Patent No. 247,925, dated October 4, 1881.

Application filed June 8, 1881. (No model.)

To all whom it may concern:

Be it known that I, JOSHUA KIDD, a subject of the Queen of Great Britain, residing at Fern Bank, Wandsworth Common, Surrey county, England, have invented new and useful Improvements in Apparatus for Enriching Gas by Admixture of Hydrocarbon Vapors, of which the following is a specification.

My present invention relates to improvements in the invention for which Letters Patent No. 227,549 were issued jointly to myself and James Livesey for an apparatus for enriching gas by mingling with it the heated vapors of hydrocarbon naphthaline or other hydrocarbons.

Prior to my invention illuminating-gas has been enriched by mingling therewith the heated vapor of naphthaline or other hydrocarbons, and a variety of apparatus have been devised for this purpose, such apparatus consisting, usually, of a carbureting-vessel, the hydrocarbon in which has been heated by the direct heat from non-carbureted-gas flames and by conducted heat from gas burning at a distance from the vessel. In all of these methods of carbureting gas the whole mass of hydrocarbon in the vessel must be melted or raised to a considerable degree of heat before carburation of the gas takes place.

The object of my invention is to lessen the time required for carburation by causing a current of hot gas to impinge directly upon the surface of the hydrocarbon placed in the vessel. The surface or upper layer by thus heating it begins to vaporize and mixes with the heated gas long before the entire mass is heated or liquefied.

A further object of my invention is to provide a movable device for regulating the mixture of gas and hydrocarbon vapor, so that the amount of carburation can be regulated and instantly controlled by the gas-consumer. This object is attained by so arranging the apparatus that more or less uncarbureted gas can be made to pass directly to the burner without entering into the vessel containing the heated hydrocarbon, all as hereinafter described.

In the drawings, Figure 1 is a section taken on a vertical central plane through the said apparatus. Fig. 2 is a horizontal section taken on the line xx . Fig. 3 is a section taken on a

vertical plane through an apparatus constructed upon a slightly-modified plan.

A indicates the carbureting-vessel, which may be of spherical or of cylindrical form, or of any other convenient shape. It is provided at its upper part with one or more apertures, a , through which the naphthaline or other hydrocarbon is fed in sticks or other solid form, these apertures being each provided with a screw-cap, B, by means of which the vessel can be tightly closed after it has been charged.

C C indicate a set of ordinary burners that are employed for illuminating and heating purposes, and D the main gas-pipe through which the supply of illuminating-gas is derived. The gas from the pipe passes over an extended heating-surface before passing to the carbureting-vessel, and as a means of providing such extended heating-surface I arrange above the burners a heater, E, consisting of a metal shell that can be composed of two disks, ee , each having a central opening, F, formed through the same, and each being provided upon its inner face with a number of corrugations that form passages so arranged that the gas will flow through the same in order to be thoroughly heated. As shown in Figs. 1 and 2, the opening through the heater, which is formed by these openings F in the disks or halves of the heater, is divided into two parts by a thin metal plate or disk, F' , that also lies between the two halves of the shell, in order that the gas will flow from pipe D through opening F in the upper portion of the heater; thence out to and around the periphery of partition F' , and back through the passages in the lower portion of the heater to the pipe H. These passages in the heater may be a series of annular corrugations, G, with radial corrugations g connecting the same, or each half of the heater can be provided with a spiral corrugation and numerous radial passages.

It will be observed that the intermediate metal partition-plate does not close the outer channel adjacent to the meeting-rims of the halves of the shell, so that the currents of gas from pipe D will impinge upon and be split by the partition-plate into divided currents flowing outward through the corrugations of the upper half, passing around the periphery of the

partition and then back through the corrugations of the lower half to the gas-pipe H, that connects with the heater, and establishes portion of a pipe-connection between the heater 5 and the carbureting-vessel. The pipe H, that is preferably made of copper or other good conductor of heat, connects with a casing, H', that surrounds and forms a chamber around the pipe I, that constitutes a continuation of pipe 10 H and enters the carbureting-vessel. The branch pipes L that support the burners lead from the chamber L', formed by the said shell, around the pipe which leads into the carbureting-vessel, said chamber communicating with 15 the carbureting-vessel, whereby the gas that has been enriched in the latter can pass up into the said chamber L', and thence out through the branch pipes to the burners.

The pipe I is provided with ports *i i* opening 20 into the chamber L', that forms a passage between the burner-pipes and the carbureting-vessel. Within the pipe I is a hollow cylindrical valve, K, open at both ends, and provided with ports K', (one being here shown,) 25 which ports can be brought to deliver into the ports *i* of the pipe I, or to close the same either wholly or in part. The means provided for rotating this valve consist of a rod, M, supporting the valve by a yoke, and passing down 30 through a tube, N, that is secured at its lower end in the bottom of the carbureting-vessel. This rod also passes through a suitable stuffing-box, n, and nut n', below the carbureting-vessel, and is provided with a milled head, O, or a 35 handle, so that it can be turned in order to operate the valve.

The operation will be as follows: The carbureting-vessel being charged with the sticks or other solid form of hydrocarbon, and the 40 valve within pipe I turned so as to close the ports in said pipe, the gas will flow through the heater and the pipe I into the carbureting-vessel, and thence up through the chamber to the burners. Being lighted at the burners the 45 ascending heat will impinge against the heater, and thus heat the gas flowing through the same, so that the heated gas passing into the carbureting-vessel will impinge upon the surface of the hydrocarbon and vaporize the same, 50 whereby the vaporized hydrocarbon will mingle with the gas and enrich it. In this way but a short time will be required for carburation, since by conducting the heated gas down from the heater to the carbureter it will rapidly vaporize the hydrocarbon, and also the heat from the gas-flame will be conducted down to the vessel by means of the pipes, which become rapidly heated by the said flame.

In order to regulate the commingling of the 60 gas and hydrocarbon vapor, so that the amount of carburation can be regulated and instantly controlled by the gas-consumer, the operator

will turn the valve so as to open the ports opening into chamber L' to a less or greater extent, as may be required, whereby the gas 65 flowing directly from the heater into said chamber will pass to the burners, whereby more or less uncarbureted gas can be made to pass directly to the burner without entering the vessel containing the hydrocarbon.

It will be observed that the carbureting-vessel is surrounded by a jacket, R, which protects the same from cold, and which can also be made highly ornamental, and, also, that the casing H constitutes a jacket for protecting the pipe and 70 the vessel from cold.

In the modification shown in Fig. 3 the gas flows through the gas-pipe D to a coil or bend, E, (which is arranged above the burner, and which subserves the purpose of the heater 80 shown in Fig. 1,) through pipe I into the carbureting-vessel, and thence out through pipe L to the burner, where the flame heats the said coil or bend, and thus heats the gas that flows into the carbureter.

I do not broadly claim warming or heating the gas before it reaches the carbureting-vessel for the purpose of enriching the gas before the entire mass of hydrocarbon is heated, as such, broadly, is not my invention.

Having thus described my invention, what I claim as new, and desire to secure by Letters Patent, is—

1. The combination, with the carbureting-vessel, of the burner, the gas-heating chamber 95 provided with a series of channels or corrugations, the pipe arranged to conduct the gas from the gas-heater to the carbureting-vessel, a valve arranged to open and close the ports in said pipe, and a chamber around said pipe 100 leading from the vessel to the burners, whereby the gas can be in part conducted directly from the heater to the burners, or the whole of the heated gas may be directed into the carbureting-vessel, substantially as described.

2. The combination, with the pipes D H, of the gas-heating chamber E, arranged above the burners, and provided with a series of channels or corrugations and a disk or partition, F', for causing a circulation of gas through the heater, 110 substantially as described.

3. The combination, with the pipe H and casing H' of the pipe I, having ports *i i*, and the cylindrical valve K, having port K', and adapted to be operated by the rod M, to control 115 the flow of carbureted or non-carbureted gas to the chamber L', substantially as described.

In testimony whereof I have hereunto set my hand in the presence of two subscribing witnesses.

JOSHUA KIDD.
